POTTERY JUG FOR MAPLE SIRUP

Marion H. Ayres, Pomfret, Vt.

Application March 1, 1949, Serial No. 1,155

Term of patent 14 years

(Cl. D44—21)

To all whom it may concern:

Be it known that I, Marion H. Ayres, a citizen of the United States, residing at Pomfret, in the county of Windsor and State of Vermont, have invented a new, original, and ornamental Design for Pottery Jugs for Maple Sirup, of which the following is a specification, reference being had to the accompanying drawing, forming part thereof.

Fig. 1 is a perspective view of a pottery jug for maple sirup, showing my new design; and

Fig. 2 is a perspective view of the other side thereof.

I claim:

The ornamental design for a pottery jug for maple sirup, as shown.

MARION H. AYRES.
